BOOK PRESSING AND DRYING MACHINE

John N. Hicks and Marvin Ford Supy, Kingsport, Tenn., and Ralph H. McDavid, Gate City, Va., assignors to Kingsport Press, Inc., a corporation of Delaware

Application February 28, 1950, Serial No. 146,692

18 Claims. (Cl. 11—1)

1

The present invention relates generally to the art of bookbinding but more particularly to a machine for pressing and drying books.

In the art of bookbinding, a casing-in machine is employed to place a thin coating of adhesive on the outer surface of the end sheets of the body of the book, to insert the body of the book into the case or cover of the book and to deliver the assembled book to a delivery table where the operator of the machine checks each book for alignment with the cover before being pressed and dried.

In a common method used for pressing and drying, the books, after they have been assembled in the casing-in machine as described, are placed flatwise on a flat board, of approximately two feet square, resting on a dolly or low truck. The books are stacked on this board for a height of about five feet with special boards between successive layers of books and the stack rolled to a press where the books are compressed and then clamped in compressed condition. The compressed and clamped stack is then rolled to a storage space where it remains for several hours or until the adhesive between the end sheets and the inside surfaces of the book covers becomes set or dried. When the adhesive is dry, the stack of books is rolled to an examination room, where the clamps are removed and the books are unloaded for inspection.

This hand operation of pressing and drying books is expensive, time consuming and inefficient. Moreover, if there is anything faulty with the pressing and drying operations, the books in the whole stack and in other stacks are apt to be imperfect, since the process does not lend itself to the discovery of such faults until after the pressing and drying operation has been completed on the entire batch.

Machines have been proposed to press and dry books automatically, but these are comparatively complicated and expensive, and do not lend themselves to quick adjustments and controls.

One object of the present invention is to provide a new and improved machine for pressing and drying books, which is simple but nevertheless efficient in operation, which has maximum of capacity for the amount of space occupied by the machine, which although automatic in certain phases is still at all times under immediate control of the operator as to the rate at which the books are passed through the machine and the length of each heating cycle, and which lends itself to easy adjustments for the accommodation of books of different sizes.

Various other objects of the invention will be apparent from the following particular description and from an inspection of the accompanying drawings, in which:

2

Fig. 1 is a side elevation, somewhat diagrammatic, of a book pressing and drying machine embodying the present invention;

Fig. 2 is a top plan view, also somewhat diagrammatic, of said machine;

Fig. 3 is a perspective of one of the inner movable pressing and drying plates and its supports;

Fig. 4 is a perspective of one of the outer pressing and drying plates with its supports adapted to cooperate with the inner pressing and drying plate shown in Fig. 3;

Fig. 5 is a front end view, somewhat diagrammatic, of the machine;

Fig. 6 is a vertical section taken on lines 6—6 of Fig. 7;

Fig. 7 is a vertical section taken on lines 7—7 of Fig. 1, but on a larger scale;

Fig. 8 is a side elevation of the hand operated microswitch mechanism for initiating and controlling each complete cycle of operation of the machine;

Fig. 9 is a side elevation of part of the ratchet and pawl clutch mechanism controlling the feed of the books through the machine;

Fig. 10 is a section showing the control valve mechanism for the air cylinder operating the feed mechanism for the books through the machine;

Fig. 11 is a detail of the machine showing in particular, a transverse vertical section of the conveyor belt for advancing the books one step from one pressing station to another;

Fig. 12 is a section of the machine taken along the lines 12—12 of Fig. 11 and showing details of the upper run of the conveyor belt;

Fig. 13 is a top plan and sectional view of the upper run of the conveyor belt taken along lines 13—13 of Fig. 12;

Fig. 14 is a front elevation of the solenoid air valve unit controlling the operation of the pneumatic power unit for the movable pressing and drying plates, the outer casing for said unit being shown in vertical section;

Fig. 15 is a top plan view somewhat diagrammatic of the air valve part of the unit shown in Fig. 14; and

Fig. 16 is a vertical simplified composite section somewhat diagrammatic of the solenoid air valve unit of Fig. 14 shown in development and taken approximately along the lines 16—16 of Fig. 15, the different parts of the section being all turned into one vertical plane to facilitate the showing of communication between the ports.

When books, one at a time at intervals of one book about every two or three seconds, are emitted from the casing-in machine to the casing-in table, the operator checks the books for alignment with the covers and then places them in a feeder trough of the book pressing and

drying machine embodying the present invention.

The book pressing and drying machine comprises in general two pairs of continuous cover pressing and sheet drying devices in the form of plates arranged parallel to and abreast of each other along the machine and defining two ways along which the books are adapted to be advanced step by step under immediate control of the operator and two pairs of pressing devices associated with said plates respectively for forming the crease or hinge joints in the covers. Along the bottom of each way is the top horizontal run of a conveyor belt on which the books are placed on their backs in tandem, dogs or pushers being arranged along the belt to engage the books and move them along the way as the belt is moved. The two outside pressing and drying plates are stationary, while the two inside pressing and drying plates are movable towards and from their corresponding outside plates into closed position to press the books, or into open position to release them for advancement along the ways. A manually operable member is provided for controlling each cycle of operation of the machine. When this control member is actuated by the operator, the following cycle of operation is performed: The two inside plates are moved simultaneously from their closed or book pressing position to their open or book releasing position; the two belts in the two ways are operated in unison to advance the released books one step, i. e., from one pressing and drying station to the next pressing and drying station; and the inside plates are then returned to their closed or book pressing position. The machine remains in this condition until the operator again actuates the control member.

Referring to the drawings, the improved machine, more specifically, comprises a table 10 supported on a frame structure 11, which in turn is desirably mounted on casters 12 (Figs. 1 and 5) to permit easy transportation of the machine into any desired locality. The machine defines two parallel ways 13 (Figs. 2, 5, and 6) along which two rows of books A in tandem are fed step by step. Each of these ways 13 is formed by a pair of continuous opposed heating and pressing devices desirably in the form of plates 14 and 15 (Figs. 1-5, 7) extending along the machine and relatively movable towards and from each other in a manner to be hereinafter described. Along the bottom of each of these ways 13 is the upper flight or run 16 of an endless feed belt 17, of the roller link sprocket chain type (Figs. 1, 2, 7 and 11-13), passing over a pair of sprocket wheels 18 and 19 at the opposite ends of the belt run and operated in steps in the manner to be hereinafter described. This feed belt or chain 17 comprises a series of side links 20 with rollers 21 therebetween. The rollers 21 on the upper belt run 16 ride over a track 22 which supports said run horizontally against sagging and which is retained in grooves 23 in respective spacer blocks 24. These spacer blocks are connected to and between side frames 25 to form therewith a unit supported on the table 10 for sideways movement thereacross, so that sideways adjustments in the position of the belt 17 is permitted in a manner and for the purpose to be described.

For pushing the books along the ways 13 with the upper belt run 16, the belt 17 has a series of dogs or pushers 26 spaced therealong according to the desired spacing between the books.

This pusher 26 comprises a roller 27 adapted to engage the edge of the book between the covers and supported at the outer end of an arm 28, the inner base end of which is flanged for attachment to the belt 17, in a manner to be described.

For supporting the lower belt run, there is provided idler rollers 29 (Fig. 1 and 11) slidable along respective axles 29^a to accommodate for adjustments in the sideway position of the conveyor belt 17 and provided with annular shoulders 29^b to support side flanges 29^c on the belt links 20.

The belt links 20 are detachable and reversible, to permit any single link 20 at a region where it is desired to attach a pusher 26 to be reversed and to employ thereby the flange 29^c on the reversed link for the attachment of the flanged base of the pusher arm 28, through the use of a screw stud 29^d. The link flanges 29^c are desirably all perforated to receive the stud 29^d at any section along the belt 10, when the link 20 at said section is reversed.

At the book entry end 30 of the machine, there are provided beyond the ends of the plates 14 and 15 two feeder troughs 31 (Figs. 1, 2 and 5) in line with the ways 13 respectively. These feeder troughs 31 comprise a fixed center wall member 32 and fixed side plate members 33 flanking said center wall member and spaced therefrom to define therewith the troughs 31. The upper belt runs 16 extend along the bottom of these troughs 31 and serve to feed the books placed in said troughs by the operator into the ways 13 between the plates 14 and 15.

Each of the heating and pressing plates 14 and 15 comprises a pair of long steel flat sheets 36 and 37 (Figs. 3, 4 and 7) separated by upright spacer bars 38 and fastened together by bolts (not shown). The spacer bars 38 are arranged at intervals along the plates to define housings for electric heating elements 40. Each of these heating elements 40 is backed with an asbestos sheeting 41 and is pressed directly against the inner metal sheet 36 by a thin metal plate 42 bearing against said asbestos sheeting 41 through screws 43 threaded into the outer metal sheet 37.

The heating elements 40 are connected to outlets 39 (Fig. 1) by means of conductor cords 39^a and are controlled by thermostats 44 located at the top of the machine. There are four of these thermostats 44, two on each side of the machine. Each of the four plates 14, 14, 15 and 15 is controlled by a corresponding thermostat 44 which can be manually set through a control handle 45 and which is responsive to a thermometer (not shown) located in the corresponding plate assembly. The temperature can be controlled, as for example, from room temperature to 210° F.

A pressing device or jaw 50 (Figs. 3, 7 and 11), for creasing the hinge grooves in the covers of the books and in the sheet paper inserts and in the form of a long thin narrow horizontal metal bar, is attached to the bottom of each plate unit 14, 14, 15 and 15. Each jaw bar 50 is held in place by an angle iron 51, running the full length of the plate assembly. One horizontal leg of angle iron 51 is clamped up against the jaw, while the other vertical leg extends upwardly into the space between the two sheets 36 and 37 and is secured to the outer sheet 37 by cap screws 52 (desirably of the allen head type), passing through said sheet 37 and threaded into

a backing plate 49 for said angle iron. Each jaw bar 50 can thereby be adjusted outwardly with respect to its corresponding presser assembly and can be replaced by a jaw bar of any desired creasing configuration.

The creasing jaws 50 being affixed to and rigid with the pressing plates 14 and 15, the position of these jaws will be fixed and predetermined with respect to said plates, and the depth of indentation produced by these jaws will be determined solely by the extent to which the jaws project beyond the respective pressing faces of said plates.

Each of the outer plates 15 is mounted in stationary position, but is adjustable to accommodate books of varying thicknesses and also to regulate the pressure desired to be exerted on the books, while the opposed inner plate 14 is mounted for movement towards and from said stationary plate 15. For supporting each plate 15 in adjustable stationary position described, there is secured thereto a plurality of support brackets 55 (Figs. 1, 2, 4, 5 and 7), each comprising a pair of substantially triangular plates 56 spaced at their top corners by a block 57 and at their bottom by a block 58 on the outer side or corner of the bracket and by a bar 60 on the inner side or corner. The bar 60 constitutes an upward angular extension of a plate 61 forming the base of the bracket 55 on which the triangular plates 56 rest and to which they are secured. The plates 56 are secured to the spacer members 57, 58 and 60 by cap screws 62, shown of the allen head type.

For adjustably securing the outer plate 15 to the brackets 55, there are provided hooks 65 in the form of angle pieces, each having a horizontal leg 66 secured to a corresponding spacer bar 38 between the sheetings 36 and 37 of said plate by a cap screw 68 (desirably of the allen head type) and having a depending leg 70 caught onto the spacer block 57 of a corresponding bracket 55 with a vertical slide fit. The plate 15 is thereby suspended from the upper ends of the support brackets 55. The vertical position of the plate 15 with respect to the brackets 55 can be adjusted by means of hand screws 71, each threaded into the horizontal leg 66 of a corresponding hook 65 and impinging upon the upper end of the corresponding bracket spacer block 57. Additional fastening means between the outer plate 15 and the brackets 55 may be provided in the form of hooks 72 (Fig. 7) secured to the outer sheet 37 of said plate by screws 73 and caught over the edge of respective bars 60 in a manner to permit vertical adjustment of the plate through the hand screws 71.

Each bracket base plate 61 rests on the machine table 10 and has sides 75 (Figs. 2 and 4) projecting beyond the bracket plates 56 and provided with elongated slots 76 for cap screws 77 (desirably of the allen head type) threaded into said table. This slot and screw arrangement guides the bracket 55 for adjusting movement across the table 10 and permits locking of the bracket in adjusted position.

For quickly adjusting the outer pressure plates 15, there is provided for each of said plates a hand wheel 80 (Figs. 1, 2, 5 and 7) arranged on one side of the machine near one end and connected to a drive spindle 81 which is journaled in a fixed bearing 82 affixed to the frame structure of the machine and which is held against axial movement in said bearing by suitable collar means 83. This drive spindle 81 is threaded

into the spacer block 58 between the plates 56 of the bracket 55 at the front end section of the machine. A series of spindles 86, similarly journaled in respective bearings 82, are similarly threaded into the spacer blocks 58 of the other brackets 55 and are rotated in unison from the main drive spindle 81 through sprocket and chain drives 87. Operation of the hand wheel 80 thereby causes the corresponding outer pressure plate 15 to be moved in and out with respect to its associated inner plate 14, while maintaining parallelism with the latter plate. Each outer plate 15 can be locked in adjusted position to the table 10 by means of the screws 71.

The turning of the hand wheel 80 not only moves the corresponding outer pressure plate 15 with respect to the associated inner pressure plate 14, but also serves to move the upper run 16 of the related feed belt 17 transversely and horizontally to maintain said run centered with respect to the way 13 defined by said plates. To that end, each of the spindles 81 and 86 has a threaded section 90 (Fig. 7) screwed into the corresponding spacer block 58, as already described, and a section 91 of smaller diameter, having twice as many threads per inch as the section 90, screwed into one of the side frames 25 of the supporting structure for the upper belt run 16. The sprockets 18 and 19 (Figs. 1 and 2) carrying each of the feed belts 17 are splined to their respective shafts to permit them to be moved along said shafts when the belt 17 is moved sideways by the operation of the hand wheel 80.

With the arrangement as described, as each outside pressure plate 15 is moved in and out with respect to the corresponding inside pressure plate 14 through the operation of the associated hand wheel 80, the upper feed belt run 16 moves only half as much, so that this belt run remains always centered directly under the center of the book, when the book is compressed between the plates 14 and 15.

The inner pressure plates 14 are mounted for movement towards and from their related outer pressure plates 15, to release the books between said plates and to permit the books to move step by step along the ways 13 into successive pressing and drying stations. To that end, there are provided (Figs. 3 and 7) a series of plate supporting brackets 95 in the form of angle bars spaced along the machine and each having a horizontal leg 96 and a vertical leg 98, the horizontal leg being arranged below the table 10 and resting on a series of short rollers 97 to permit said leg to roll therealong. The inner plate 14 is adjustably secured to the vertical bracket legs 98 by hooks 100 in the form of angle pieces, each having a horizontal leg 101 secured to a corresponding spacer bar 38 between the sheetings 36 and 37 of said plate by a cap screw 102 (desirably of the allen head type) and having a depending leg 103 caught onto the upper section of the vertical leg 98 of the corresponding support bracket 95 with a vertical slide fit. The plate 14 is thereby suspended from the support brackets 95 and its vertical position with respect to said brackets can be adjusted by means of hand screws 104, each threaded in the horizontal leg 101 of a corresponding hook 100 and impinging upon the upper end of the corresponding bracket leg 98.

The inner pressure plates 14, upon manual operation of a control member to be described, are moved away from their corresponding outer

pressure plates 15 into open position to release the books therebetween at one pressing and drying station and to permit them to be moved along the ways 13 by the feed belt 17 to the next pressing and drying station and are then moved towards their corresponding outer pressure plates 14 into closed position to press and dry the books at this next station until the next manual operation of said control member. For effecting these operations of the plates 14, there is provided a shaft 110 (Figs. 1 and 7) extending along the bottom of the machine and supported in pillow block bearings 111 mounted upon the bottom cross members 112 of the machine frame 11. This shaft 110 effects by its operation the movement of the plates 14 towards and away from the corresponding plates 15 and is rocked for that purpose by an individual power unit in the form of an air cylinder 113 slanting upwardly and outwardly towards the side of the machine and containing a reciprocable piston 114 connected to a piston rod 115. This piston rod 115 is pivotally connected at its outer lower end to a crank arm 116 affixed to the rockshaft 110.

The transmission between the rockshaft 110 and the inner plates 14 comprises a plurality of vertical slides 118 (Figs. 6 and 7) in the form of flat bars arranged in pairs, the two slides of each pair facing each other and rigidly connected together at the bottom by the blocks 119 to form a unit. The two slides 118 of each unit are guided for vertical movement between two corresponding guide plates 120 secured to the frame structure of the machine. These two guide plates 120 extend upwardly and flank the corresponding pair of opposed support brackets 95 between the plates 14. The two slides 118 of each unit are in face engagement with these guide plates 120, flank the corresponding pair of opposed plate support brackets 95, and slidably engage these support brackets along their edges.

For moving each pair of slides 118 up and down in unison, the rockshaft 110 has secured thereto a corresponding crank arm 122 pivotally connected to one end of a link 123, the other end operating these slides through a toggle device comprising two levers 125 and 126 joined together at 127 end to end but not in line, the upper lever 125 having an angular extension 128 pivotally secured to said link 123. The outer or upper end of the upper toggle lever 125 has a fixed pivotal support comprising a bolt 131 secured in fixed position to the fixed guide plates 120 and passing through the corresponding slides 118. A roller 132, embracing this bolt 131 and extending between the guide plates 120, passes through aligned elongated slots 133 in the slides 118 with a snug slide fit to permit these slides to move upwardly past the roller 132, while being held thereby against edgewise displacement.

The lower toggle lever 126 is pivotally secured to the slides 118 by a bolt 135 extending through aligned elongated slots 136 in the guide plates 120 and carrying rollers 137 at its ends fitting into said slots to effect a slide bearing connection between said rollers and said guide plates. By means of this arrangement and the slot and roller connections 131, 132 and 133 associated with the upper toggle lever 125, the two slides 118 of each unit, as they move up and down, are held in vertical alignment with the two flanking guide plates 120.

As the rockshaft 110 is moved clockwise (Fig. 7) through operation of the piston 114, the

upper toggle lever 125 swings counterclockwise about its pivotal connection 131 with the guide plates 120 and thus moves the lower toggle lever 126 substantially endwise upwardly, causing thereby the two slides 118 of each unit to move upwardly through the pivot connection 135 of said lower toggle lever 126 with said slides. The reverse downward movement of the slides 118 of each unit is effected when the rockshaft 110 is moved counterclockwise (Fig. 7) through operation of the piston 114.

For moving the pressure plates 14 in and out in response to the vertical movement of the slides 118, the two slides of each unit carry four pins 140, two on each side having tight fits at their ends with said slides. These pins 140 are flush with the outer surfaces of said slides, so that they can move freely up and down without rubbing on the inside surfaces of the guide plates 120. Rollers 141, embracing the pins 140 and extending into elongated cam slots 142 in the plate support brackets 95, serve as bearings for the slides 118 and for said brackets in their relative movements. Two of these elongated slots 142 are arranged in each bracket 95 extending parallel and inclined upwardly and sideways outwardly.

According to the foregoing arrangement, when the two slides 118 of each unit are in their lowermost position, as shown in Fig. 7, the rollers 141 are in the lower portions of their respective cam slots 142. In this position of the slides 118, the inner plates 14 are in their outward operative position, cooperating with their corresponding outer plates 15 to press and dry the books. When the slides 118 are moved upward, the rollers 141 carried by said slides, and riding in the inclined cam slots of the brackets 95 supporting the plates 14, move said plates inwardly towards each other and away from their corresponding plates 15 to release the books for feed along the ways 13. The movement of the slides 118 downward returns the inner plates 14 to their pressure applying position.

The operation of the air power unit, by which the movements of the inner plates 14 with respect to the outer plates 15 are effected, is manually controlled through the operation of a solenoid and spring operated air control valve 150 (Fig. 1) located on one of the bottom cross-members of the frame structure under the front or feeder entry end of the machine. This air control valve 150 serves to control the air under pressure coming from a suitable source of air pressure (not shown) through a pipe 146 leading into a pressure regulating and distributing valve device 147 and has its inlet connected to this device by a pipe 148. The speed of the opening and closing movements of the pressure plates 14 can be controlled by regulating an exhaust cock 149 on the air control valve 150.

The air control valve 150 may be of any suitable well known type, but in the specific form shown in Figs. 14, 15 and 16 is of the so-called Ross 4-way type having a solenoid 250 controlled by a microswitch 151 (Figs. 1 and 8) in the circuit of said solenoid. The air valve 150 shown for purposes of illustration has one pair of spring-pressed poppet valves 251 and 252 with respective stems 253 and 254 operated simultaneously by a bar 255 forming a transverse extension of a walking beam 256 and another pair of spring-pressed poppet valves 257 and 258 with respective stems 259 and 260 operated simultaneously by a bar 261 forming another transverse extension

of said walking beam. This walking beam 256 is pivoted at 262 and has one end pivotally secured to the plunger of the solenoid 250 and has its other end operating the poppet valves 251, 252, 257 and 258 through its transverse extension bars 255 and 261.

The air valve 150 has the intake connection 148 communicating with two valve chambers 266 and 267 through the valves 252 and 257. The valve chamber 266 communicates with a valve chamber 268 through ports 270 and 271 in said chambers respectively and a conduit 272 therebetween. This valve chamber 268 has a connection 177 with one end of the air cylinder 113.

The valve chamber 267 communicates with a valve chamber 273 through ports 274 and 275 in said chambers respectively and a conduit 276 therebetween. The valve chamber 273 has a connection 178 with the opposite end of the cylinder 113.

The air valve 150 also includes two valve chambers 278 and 280 with exhaust ports 281 and 282 respectively communicating with a port 283 in an exhaust chamber 284 through conduits 285 and 286 respectively. This exhaust chamber 284 has an outlet connection 287 with the exhaust cock 149.

The air valve 150 is shown in Fig. 16 in deenergized position of the solenoid 250. In this position, a spring 288 acting on the beam 256 closes valves 251 and 252 and opens valves 257 and 258. The arrows in full lines in Fig. 16 indicate the direction of flow of the air right after the solenoid 250 has been deenergized in the position shown. When the solenoid 250 is energized, the valves 251 and 252 are opened and the valves 257 and 258 are closed and the flow of air is in the direction of the arrows shown in dotted lines in Fig. 16.

The microswitch 151 is mounted between the inner plates 14 near the inlet ends thereof on a support 152^a (Fig. 8) secured to the table 10 and is controlled by a trip lever 152. This trip lever 152 comprises a bar 153 pivoted at 154 to the side of the switch support 152^a and having secured to its forward end a sensitive spring plate 155 adapted to be pressed by the operator and to transmit, with minimum of shock and impact, movement closing the microswitch 151.

The microswitch 151 comprises a spring-pressed plunger or tappet 156 adapted to act on the switch contacts to close them when said plunger is pressed inwardly and to permit the contacts to open when spring released outwardly. A bell crank 157 is pivoted at 158 on an arm 160 secured to the switch support 152^a and has one arm 161 engaging the plunger 156 and the other arm 161^a carrying a roller 162 riding on the upper edge of the lever bar 153.

For automatically locking the microswitch 151 in closed position for a period of each operating cycle, the rear end of the lever bar 153 has a catch conformation 163, formed by a curved notch 164 defining a heel 165. Cooperating with this catch conformation 163, is a latch bar 166 passing with clearance through the table 10 and through a collar 167 secured to said table and pivotally suspended from said collar 168. The pivot 168 is located off center with respect to said latch bar to cause the latter when released to swing gravitationally into the position shown by the dot and dash lines in Fig. 8 and hold the microswitch 151 in closed position. The latch bar 166 is provided at its upper end with a tongue 170 having an upper curved end 171 to permit

it to slide easily under the heel 165 of the catch conformation 163 at the end of the lever bar 153 and to fit substantially conformably in the notch 164 of said catch conformation, when said latch bar 166 is cammed into the position shown by the full lines in Fig. 8.

For effecting such cam action on the latch bar 166 to release the microswitch 151 into open position, there is provided at the front end of the machine, attached to the bolt 135, a rod 173 which connects the lower toggle lever 126 of the front toggle device to the corresponding front slide unit 118, 118 and which is guided for vertical movement in a guide hole (not shown) in an upper frame member 174 (Fig. 5). The upper end of this rod 173 carries a cam cone 175 (Fig. 8) which is held in adjusted position thereon by a set screw 176.

As the cam cone 175 is moved upward by the upward movement of the slide unit 118, 118, it strikes the lower end of the latch bar 166 while suspended in the switch locking position shown by the dot and dash lines in Fig. 8 and causes it to move counterclockwise about its pivot 168 into the position shown by the full lines in Fig. 8. In this latter position, the lever bar 153 is permitted to turn about its pivot at 154 into position to release the microswitch 151 and to permit it to open.

In the position shown in Fig. 8, the microswitch 151 is open, the solenoid operating the air valve 150 is deenergized, the valve 150 is in position to admit air under pressure into the upper end of the air cylinder 113 through hose connection 177 (Figs. 7 and 16), the piston 114 is in its lowermost position in the air cylinder 113, and the lower end of said air cylinder is open to exhaust through hose connection 178. In such open position of the microswitch 151, the piston rod 115 is in fully projected position shown in Fig. 7, the slide units 118, 118 are in their lowermost position, and the plates 14 are moved toward their corresponding plates 15 to press and dry the books in the two ways 13.

When the operator depresses the spring plate 155 on the trip lever 152, this lever is turned about its pivot at 154 and the microswitch 151 is thereby closed. At the same time, the latch bar 166 is released and permitted to swing about its off center pivot 168 into the position shown by the dot and dash lines in Fig. 8. In this released position, the latch bar 166 blocks the return of the trip lever 152 into full line position shown and holds said trip lever in the switch closing position, even though the operator has released the spring plate 155 on said lever.

As soon as the microswitch 151 is closed by the operator's depression of the spring plate 155 as just described, the air valve 150 is operated by the energized solenoid into position to admit air under pressure into the lower end of the air cylinder 113 through the hose connection 178 and to exhaust air from the upper end of the cylinder through the hose connection 177. This causes the piston rod 115 to move upwardly in the air cylinder 113 and rotates thereby the rockshaft 110 clockwise to cause the slide units 118, 118 to move upwardly. This upward movement of the slide units 118, 118 causes the plates 14 to move inwardly towards each other and away from their corresponding plates 15 and to release the books in the ways 13 for the next feeding step.

While the front end slide unit 118, 118 is moving upwardly, the cam cone 175 carried by said

unit through the rod 173 cams the latch bar 166 into position to permit the trip lever 152 to swing about its pivot 154 into the position shown by the full lines in Fig. 8, so that the microswitch 151 under the action of the spring on its plunger 156 is permitted to open. This action opens the circuit of the solenoid controlling the air valve 150 and causes said valve under spring action to move into position to admit air under pressure to the upper end of the air cylinder 183 through the hose connection 177 and to exhaust the air from the lower end of the cylinder through the hose connection 178. This causes the rockshaft 110 to rotate counterclockwise (Fig. 7) and to move thereby, through the slide units 118, 119, the plates 14 into book pressing and drying positions. The plates 14 remain in this active position until the operator again depresses the spring plate 155 on the trip lever 152.

While the microswitch 151 is open and the plates 14 are in book pressing and drying positions, the feed belts 17 are stationary. But when the plates 14 are in open or book releasing position due to the closing of the microswitch 151, the feed belts 17 are operated just sufficiently to move the books in the ways 13 one step along said ways to the next pressing and drying station. The feed belts 17 then come to rest, while the plates 14 are moving towards their book pressing and drying position.

For operating the feed belts 17 in the manner indicated, there is provided another individual power unit comprising a long slender air cylinder 185 (Fig. 1) located underneath the table 10 and inclined upwardly and rearwardly of the machine. This air cylinder 185 contains a piston 186 operating a piston rod 187 secured to an endless inclined chain 188 passing over a sprocket wheel 190 (Fig. 9) at the upper end of the chain run and passing over a sprocket wheel (not shown) at the lower end of the run. This sprocket wheel 190 is supported for free rotation on a shaft 191 journaled in suitable bearings secured to the frame structure of the machine and has a ratchet and pawl connection with said shaft comprising a ratchet wheel 192 keyed or otherwise rigidly secured to said shaft and a pawl 193 pivotally supported on the sprocket wheel 190 by a pivot screw 194 and yieldably pressed into engagement with said ratchet wheel by a spring 195.

Keyed or otherwise secured to the shaft 191 is another sprocket wheel 196 driving a shaft 197 (Figs. 1 and 2) through an endless chain 198 passing over said sprocket wheel 196 and over a sprocket wheel 200 secured to said shaft 197. The shaft 197 carries the sprocket wheels 18 over which the two endless book feeding belts 17 in the two ways 13 pass.

When the upper run of the chain 188 to which the outer end of the piston rod 187 is connected is moved to the left (Fig. 1) by the action of said piston rod, the pawl 193 engaging the tooth on the ratchet wheel 192 rotates said ratchet wheel counterclockwise (Fig. 9) and causes corresponding rotation of the shaft 191. Such rotation of the shaft 191 causes the rotation of the drive shaft 197 of the feeder belts 17 in the direction to cause the upper runs 16 of these belts to advance the books along the ways 13 one step. The length of this feed step depends on the length of movement of the piston rod 187.

When the upper run of the chain 188 is returned to the right (Fig. 1) by the return movement of the piston rod 187, the sprocket wheel

192 rides idly on the shaft 191, so that this return movement of the piston rod is not transmitted to the feed belts 17.

For controlling the operation of the air power unit 185, 186, there is provided a mechanically operated air control valve 205 (Figs. 1 and 10) which may be of any well known type, but which is illustrated in Fig. 10 of the so-called Lehigh four-way type. In the specific form shown, this air valve 205 comprises a slide valve 199 connected to a lever 210 and slideable in a filter sleeve 200. The air valve 205 has an inlet port 201, two ports 202 and 203 on opposite sides of the valve connected to opposite ends respectively of the air cylinder 185 and exhaust chambers 205^a and 205^b blocked off or opened in accordance with the axial position of the slide valve member 199.

The valve 205 has its inlet 201 connected to the pressure regulating and distributing valve device 147 through a pipe 204 (Fig. 1) and is controlled from the rockshift 110 through a crank 206 (Fig. 10) rigidly attached to said shaft and carrying a cam 207 with an open slot 208. The air valve 205 is operated from the lever 210 carrying a roller 211 extending into the cam slot 208.

While the rockshaft 110 is in the position indicated in Fig. 10, the air valve 205 is in position to admit air under pressure into the upper end (Fig. 1) of the air cylinder 185 through a pipe connection 213 and to exhaust the air from the lower end of the air cylinder through a pipe connection 214. The piston rod 187 will, therefore, be in the limit of its inward position in the air cylinder 185.

When the rockshaft 110 is rotated counterclockwise (Fig. 10) through the manipulation of the trip lever 152 by the operator in the manner already described and while the plates 14 are opening up to release the books from pressure, the lever 210 moves the air valve 205 in position to admit air under pressure to the lower end of the air cylinder 185 through the pipe connection 214 and to exhaust the air from the upper end of the air cylinder through the pipe connection 213. This moves the piston rod 187 outwardly from the air cylinder 185 and causes the upper runs 16 of the feed belts 17 to advance one step. The speed of advancement of these upper belt runs 16 is controlled by regulating an exhaust pet cock 216 (Figs. 1 and 10) in the air valve 205. The return movement of the piston in the air cylinder 185 is controlled by an exhaust cock 217 in the air valve 205.

While the rockshaft 110 is returning clockwise (Fig. 10), and while the plates 14 are moving into pressure applying position, the lever 210 moves the air valve 205 in position to admit air under pressure to the upper end of the air cylinder 185 through the pipe connection 213 and to exhaust the air from the lower end of the air cylinder 185 through the pipe connection 214. This moves the piston rod 187 inwardly into the air cylinder 185 and moves the belt chain 188 idly over the shaft 191.

The air cylinder 185 is long and slender and in the specific form shown may be of twenty-four inches full stroke length. However, the length of the piston stroke can be varied by placing a tube 220 (Fig. 1) over the piston rod 187 as shown. This limits the return movement of the piston rod 187 into the air cylinder 185 by an extent determined by the length of the tube 220. For example, a tube twelve inches

long over the piston rod 187 limits the effective length of the stroke to twelve inches. By removing this tube 220, a twenty-four inch stroke can be secured. With this arrangement, the books can be moved along the ways 13 twelve inches during each cycle or can be moved the full extent of the stroke (twenty-four inches). When using a twelve inch stroke, the operator places one book in each feeder trough 31 before depressing the trip lever 152. When using a twenty-four inch stroke, the operator places two books in each feeder trough 31 before he depresses the trip lever 152.

The books completely dried are discharged from the delivery end of the plates 14 and 15 on to two rows of rollers 229 and 230 (Figs. 1 and 2) arranged to slant downwardly towards a conveyor 231 on the discharge end of the table 10, so that the books on said rollers move by gravity along said rollers onto said conveyor. This conveyor 231 is not part of the machine, but is a separate unit pushed up against the machine.

A rod 232 located at the discharge end of one way 13 on one side of the machine (lower one in Fig. 2) and secured to the end of the pressure plate 15 on said side directs the books discharged from said way in upright position on their backs onto the corresponding set of rollers 229, and an inclined rod 234 secured to said rod 232 tips the books sideways as they are moved by gravity past said inclined rod. The tipped books fall onto a roller 235 which automatically rolls the book downward (Fig. 2) and causes it to fall flatwise in the clear and in line on the slanted row of rollers 229 for gravitational conveyance thereby to the conveyor 231 which carries the books to an examining table for final inspection.

A rod 236 located at the discharge end of the other way 13 on the other side of the machine (upper one in Fig. 2) and secured to the end of the pressure plate 15 on said side directs the books discharged from said way in upright position on their backs to the corresponding set of rollers 235, and an inclined rod 238 secured to the rod 236 tips the books sideways as they are moved by gravity past said inclined rod. The tipped books fall onto an inclined plate 240 which serves to slide the books flatwise in the clear and in line onto the slanted row of rollers 229 for gravitational conveyance thereby to the conveyor 231.

Although the operation of the invention has been made apparent, a brief recapitulation may be helpful.

The machine stays in closed or book pressing position until the operator depresses the trip lever 152. During this phase of operation, the plates 14 are in their outward positions pressing and drying the books in the ways 13, while the solenoid operating the air control valve 150 for the power unit 113, 114 is deenergized. This prevents the solenoid from overheating and becoming damaged in case the plates 14 are left in book heating position too long. The solenoid is energized only for a brief period (about a second or so) during each cycle when the plates 14 are opening to book releasing position.

The books remain under pressure and drying heat from the plates 14 and 15 during each cycle as long as the operator wishes. The operator terminates each cycle and initiates the next cycle by depressing the trip lever 152. While the books are under pressure and heat from the plates 14 and 15, they are protected against overheating

by the thermostats 44 controlling the heating elements 40 in these plates.

While the books are under the pressing action of the pressure plates, they are not only being heated so that the coating of adhesive on the outer surface of the end sheets of the body of the book attached to the cases or covers of the books are being dried or set, but in addition the creasing jaws 50 on said plates are producing the hinge joints or grooves in the books.

During the book pressing and heating cycle, the operator will be placing into the two feeder troughs 31, in front of corresponding dogs or pushers 26 on the upper belt runs 16, the freshly prepared books emitted from the casing-in machine.

Upon depression of the trip lever 152 by the operator, the solenoid of the air control valve 150 is energized and the valve is moved into position to actuate the air power unit 113, 114 and to cause thereby the rockshaft 110 to rotate clockwise (Fig. 7). This moves the plates 14 into open position away from their corresponding plates 15 through the upward movement of the slide units 118, 118 and releases the books in the two ways 13. While the plates 14 are moving into open position and after the books have been released, the clockwise rotation of the rockshaft 110 operates the air control valve 205 for the air power unit 185, 186 and causes the upper runs 16 of the feed belts 17 to advance one step, the length of which depends on the effective length of the piston rod 187 as determined by the presence or absence of the limiting tube 220 on said rod. This causes the books in the two ways 13 to be advanced one step to the next pressing and drying station between the plates 14 and 15 and causes the books which have been set up in the feeder troughs 31 to be advanced into the ways 13 and into the first pressing and heating station between the plates 14 and 15.

During the operations above described, the air control valve 150 is locked by the latch bar 168 into solenoid energizing position.

When the slide units 118, 118 have reached near the end of their upward movement, the latch bar 168 is actuated by the cam cone 175 into position to deenergize the solenoid of the air control valve 150 and to move said valve into position to reverse the operation of the air power unit 113, 114 and to return the rockshaft 110 counter-clockwise (Fig. 7). This causes the slide units 118, 118 to descend and the plates 14 to be moved into closed or pressure applying position with respect to the plates 15.

The return operation of the rockshaft 110 causes the return of the air control valve 205 into its initial position and reverses the operation of the air power unit 185, 186. The book advancing movement of the belt runs 16 ceases, therefore, during this phase of the cycle, since this reverse operation of the air power unit 185, 186 has an idle effect on said belt runs due to the ratchet and pawl arrangement 192, 193.

The plates 14 remain in pressure applying and drying position and the feed belts 17 remain stationary until the cycle is repeated by another manual actuation of the trip lever 152.

As the books come out of the discharge end of the ways 13, they are carried away by the conveyor 231 or may be picked up by an operator and inspected before being carried or stored away.

It should be noted that the beginning of each cycle and the length of each pressing and drying phase is under the immediate control of the op-

erator, without any danger of overheating. The operation of the machine can thereby at any instant be adapted to the prevailing conditions at the time, such as the speed at which the books are discharged from the casing-in machine, the type and size of books being assembled and the character of the adhesive employed, without the necessity of changing cams or making other material changes in the machine.

Moreover, the pressing and heating plates 14 and 15 being continuous along substantially the full length of the machine, there is assurance that the entire areas of the book covers are embraced by these plates at any operating station therealong.

Furthermore, the books are advanced by the simple but nevertheless effective expedient of conveyor belts without injury to the books, instead of clamping devices and the like which not only require comparatively expensive devices to operate, but which have the effect of injuring or marring the book covers.

Also, the machine has two production lines operated simultaneously and conveniently by a single operator and occupies space not much more than that occupied by a single production line. Moreover, these two production lines are operated simultaneously by the same operating and control devices, thereby effecting increased capacity without a corresponding increase in the cost of the machine.

While the invention has been described with particular reference to a specific embodiment, it is to be understood that it is not to be limited thereto, but is to be construed broadly and restricted solely by the scope of the appended claims.

What is claimed is:

1. In a book pressing and drying machine, the combination of a pair of opposed side pressing plate devices defining a way for a row of books, an endless conveyor belt having a book feeding run extending along the bottom of said way and adapted to receive the books thereon edgewise, a rockshaft, a first air cylinder and piston unit for oscillating said rockshaft through one cycle, a second air cylinder and piston unit for advancing said conveyor belt one step, an air control valve for said second cylinder and piston unit, a connection between said rockshaft and one plate device for moving it transversely with respect to the other device into closed position to press said books yieldably by air pressure action and into open position to release them for advance, and a connection between said rockshaft and said air control valve to cause said belt run to advance one step while said movable plate device is in open or book releasing position.

2. In a book pressing and drying machine, the combination of a pair of opposed side pressing plate devices, a slide device, an air cylinder and piston unit for moving said slide device, a connection between said slide device and one plate device for moving the latter transversely with respect to the opposed plate device into book pressing and book releasing positions, an air control valve for said cylinder and piston unit, a manually operable control member for said valve to cause said slide device to move in one direction and to move thereby said plate device towards open or book releasing position, a latch for automatically holding said control member in actuated position, and a connection between said slide device and said latch for releasing said latch while said slide device is terminating its

stroke in said direction to permit said air control valve to return to initial position and cause the slide device to return said movable plate device to closed or book pressing position.

3. In a book pressing and drying machine, a pair of opposed side pressing continuous plates defining a way for a row of books the lengths of said plates being sufficiently long to receive a series of books therealong in tandem simultaneously at different pressing and drying stations, one of said plates being movable towards and from the other to effect alternate pressing of the books between said plates and release thereof for advancement along said way, said other plate being stationary but being mounted for adjustment towards and from the movable plate, a plurality of adjusting means spaced along said stationary plate for adjustably moving said stationary plate towards and away from the movable plate, and a single control member for operating all of said adjusting means simultaneously.

4. In a book pressing and drying machine, the combination of a pair of opposed side pressing plates defining a way for a row of books, one of said plates being movable towards and away from the other to effect alternate pressing of the books between said plates and release thereof for advancement along said way, said other plate being stationary but being mounted for adjustment towards and from the movable plate, a series of supports for said stationary plate, a screw spindle threaded into each of said supports for adjusting said stationary plate towards and from said movable plate, a handle on one of said screw spindles, and chain and sprocket drive connections between said screw spindles to effect their adjustment in unison.

5. In a book pressing and drying machine, the combination of a pair of opposed side pressing plates defining a way for a row of books, one of said plates being movable towards and from the other to effect alternate pressing of the books between said plates and release thereof for advancement along said way, said other plate being stationary but being mounted for adjustment towards and from the movable plate, and an endless conveyor belt having a book feeding run extending along the bottom of the way to support the books thereon edgewise, said conveyor belt being adjustable transversely to maintain a constant relationship between the position of the book feeding run and the positions of the plates.

6. In a book pressing and drying machine, the combination according to claim 5, comprising means for adjusting said stationary plate and said belt run simultaneously but to different extents to maintain a constant relationship between the position of said belt run and the positions of said plates.

7. In a book pressing and drying machine, the combination of a pair of opposed side pressing plates defining a way for a row of books, one of said plates being movable towards and from the other to effect alternate pressing of the books between said plates and release thereof for advancement along said way, said other plate being stationary but being mounted for adjustment towards and from the movable plate, a series of supports for said stationary plate, an endless conveyor belt having a book feeding run along the bottom of said way centrally between said plates, a support for said belt run, a screw spindle threaded into each of said plate supports and into said belt run support, the number of threads per inch on the part of each of said spindles

engaging the corresponding plate support being half as many as the number of threads per inch on the part engaging the belt run support, and means for rotating said spindles in unison and to the same extent.

8. In a book pressing and drying machine, the combination of a pair of long horizontally disposed parallel pressing plates having opposed continuous faces to act simultaneously upon the opposite sides of a series of books in tandem, said plates defining a guideway for the books in their advance through the machine and affording a plurality of pressing and drying stations for each book along said guideway, the number and location of said stations varying in accordance with any variation in the number and location of the books in the series, power means for moving said pressing plates relatively to each other to open and closed positions, respectively, automatic means operated in timed relation to said power means for advancing the books step by step from station to station in the open position of the side pressing plates, and means for varying the extent of operation of said advancing means to correspondingly vary the length of the book advancing step.

9. The combination according to claim 8, wherein the book advancing means include an endless conveyor belt disposed with its upper run along the bottom of the guideway, said belt supporting the books by their backs and having pusher elements rising between the side pressing plates to engage the trailing ends of the books between their covers.

10. The combination according to claim 8, wherein the power means for moving the side pressing plates are operated in periodic cycles, coming to rest at the end of each cycle with the side pressing plates in closed position and exerting pressure against the books until the inauguration of the next succeeding cycle.

11. The combination according to claim 10, including manually operable means to initiate the operation of said power means at each cycle, and automatic means to bring the power means to rest at the end of each cycle.

12. The combination according to claim 8, wherein the power means for moving the side pressing plates include a reversible pneumatic power unit operable in periodic cycles, said pneumatic unit coming to rest at the end of each cycle with the side pressing plates in closed position and exerting a yielding pressure against the books until the inauguration of the next succeeding cycle.

13. The combination according to claim 12, including a control valve for said reversible pneumatic power unit, manual means for actuating the control valve to initiate the operation of the pneumatic unit at each cycle, and automatic means for actuating the control valve to bring the pneumatic unit to rest at the end of each cycle.

14. The combination according to claim 9, wherein the endless conveyor belt is operated by an automatically controlled reversible pneumatic power unit operable in periodic cycles, said power unit advancing the belt one step forward at the beginning of each cycle and coming to rest at the end of each cycle.

15. The combination according to claim 9, wherein the power means for moving the side pressing plates include a reversible pneumatic power unit operable in periodic cycles, said power unit coming to rest at the end of each

cycle with the side pressing plates in closed position and exerting a yielding pressure against the books until the inauguration of the next succeeding cycle, and wherein the endless conveyor

5 belt is operated by a second reversible pneumatic power unit operable in the same periodic cycles under the automatic control of the first pneumatic unit, said second pneumatic unit advancing the belt one step forward at the beginning of each cycle and coming to rest at the end of each cycle.

10 16. The combination according to claim 8, including a pair of opposed continuous creasing jaws for producing the hinge joints or grooves in the backs of the books, said jaws being fixed to the side pressing plates and projecting inwardly a predetermined distance from the book contacting faces of said plates.

15 17. The combination according to claim 9, including a pair of opposed continuous creasing jaws for producing the hinge joints or grooves in the backs of the books, said jaws being fixed to the side pressing plates at a predetermined distance above the upper run of the conveyor belt and projecting upwardly a predetermined distance from the book contacting faces of said plates.

20 18. In a book pressing and drying machine, the combination of two pairs of long horizontally disposed parallel pressing plates defining two side-by-side guideways for two series of books, with the books of each series arranged in tandem, the plates of each pair having opposed continuous faces to act simultaneously upon the opposite sides of the books in the corresponding series and affording a plurality of pressing and drying stations for each book along the corresponding guideway, the two outer side pressing plates of the respective pairs being fixed and the two inner side pressing plates of the respective pairs being mounted for movement from and toward the fixed plates to open and closed positions, respectively, a first single power unit connected to the movable plates of the two pairs for effecting their movement simultaneously, two endless conveyor

25 30 35 40 45 50 55 60 belts disposed along the bottoms of the respective guideways for advancing the books step by step from station to station in the open position of the side pressing plates of the respective series, a second single power unit connected to both of said conveyor belts for operating them simultaneously to advance the books in both series in the open position of the two pairs of side pressing plates, and automatic means for controlling the operation of the second power unit in proper timed relation to that of the first power unit.
